UNITED STATES PATENT OFFICE

117,205

DESIGN FOR A CURTAIN ROD

Philip B. Stratton, Sturgis, Mich., assignor to Hirsch Company, Sturgis, Mich.

Application July 7, 1939, Serial No. 85,876

Term of patent 14 years

To all whom it may concern:

Be it known that I, Philip B. Stratton, a citizen of the United States, residing at Sturgis, in the county of St. Joseph and State of Michigan, have invented a new, original, and ornamental Design for a Curtain Rod, of which the following is a specification, reference being had to the accompanying drawing, forming part thereof, in which the figure is a perspective view of a curtain rod showing my new design.

I claim:

The ornamental design for a curtain rod, substantially as shown.

PHILIP B. STRATTON.

CERTIFICATE OF CORRECTION.

Design No. 117,205.

October 17, 1939.

PHILIP B. STRATTON.

It is hereby certified that the name of the assignee in the above numbered patent was erroneously described and specified as "Hirsch Company" whereas said name should have been described and specified as Kirsch Company, of Sturgis, Michigan, as shown by the record of assignments in this office; and that the said Letters Patent should be read with this correction therein that the same may conform to the record of the case in the Patent Office.

Signed and sealed this 12th day of December, A. D. 1939.
